UNITED STATES PATENT OFFICE

166,720

STOCKING

Herman Spiller, Philadelphia, Pa.

Application May 22, 1951, Serial No. 15,278

Term of patent 14 years

(Cl. D47—7)

To all whom it may concern:

Be it known that I, Herman Spiller, a citizen of the United States, residing at Philadelphia, Pennsylvania, have invented a new, original, and ornamental Design for a Stocking, of which the following is a specification, reference being had to the accompanying drawings, forming part thereof.

Fig. 1 is a perspective view showing the novel stocking upon the leg of a wearer. The wearer is shown as standing on her toe.

Fig. 2 is a rear view of the same with a portion of the stocking intermediate at its ends being broken away in order to permit the showing of the portion carrying the novel design on as large a scale as possible.

I claim:

The ornamental design for a stocking, substantially as shown.

HERMAN SPILLER.
